(57) **CLAIM**

An ornamental design for a display screen or portion thereof with transitional graphical user interface, as shown and described.

DESCRIPTION

FIG. 1 is a front view of a display screen or portion thereof with transitional graphical user interface showing the first image in a first sequence representing a first embodiment of the present disclosure.

FIG. 2 is the second image of the first sequence.

FIG. 3 is the third image of the first sequence.

FIG. 4 is the fourth image of the first sequence.

FIG. 5 is the fifth image of the first sequence.

The appearance of the transitional image represented by the first sequence sequentially transitions between the images shown in FIGS. 1-5. The process or period in which one image transitions to another image forms no part of the claimed design.

FIG. 6 is a front view of a display screen or portion thereof with transitional graphical user interface showing the first image in a second sequence representing a second embodiment of the present disclosure.

FIG. 7 is the second image of the second sequence.

FIG. 8 is the third image of the second sequence.

FIG. 9 is the fourth image of the second sequence.

FIG. 10 is the fifth image of the second sequence; and, FIG. 11 is the sixth image of the second sequence.

The appearance of the transitional image represented by the second sequence sequentially transitions between the images shown in FIGS. 6-11. The process or period in which one image transitions to another image forms no part of the claimed design.

The outermost broken line rectangle in each figure illustrates a display screen or portion thereof and forms no part of the claimed design.
